UNITED STATES PATENT OFFICE

ROMEO S. WOOD, OF PLYMOUTH, MICHIGAN

PRESSURE LINE CONTROL

Application filed September 3, 1929. Serial No. 390,017.

My invention relates to a new and useful improvement in a pressure line control adapted for mounting in pressure lines for delivering of liquids and gases and particularly adapted for installation in steam lines, water lines, etc.

It is an object of the present invention to provide a pressure line control which will serve to shut off the flow of material through the pressure line dependent upon operation of the actuating mechanism which may be positioned in any desirable location and automatically operated.

Another object of the invention is the provision of a mechanism of this class whereby the flow of material through the pressure line may be shut off automatically and the line extending beyond the control drained.

Another object of the invention is the provision of a control which will serve to shut off the flow of material through the pressure line and simultaneously open the drain.

Another object of the invention is the provision of a device of this class which will be simple in structure, economical of manufacture and highly efficient in use.

Other objects will appear hereinafter.

The invention consists in the combination and arrangement of parts hereinafter described and claimed.

The invention will be best understood by a reference to the accompanying drawing which forms a part of this specification and in which,

Fig. 1 is a side elevational view of the invention.

Fig. 2 is a side elevational view of the invention from the opposite side.

Fig. 3 is a sectional view taken on line 3—3 of Fig. 2.

Fig. 4 is an enlarged sectional view taken on line 4—4 of Fig. 2.

Fig. 5 is an enlarged sectional view taken on line 5—5 of Fig. 2.

Fig. 6 is an enlarged sectional view taken on line 6—6 of Fig. 1.

The mechanism may be enclosed in a suitable housing and comprises a base 7 projecting upwardly from which are standards 8

and 9. The pressure line 10 is projected through the valve 11 which may be of any suitable type and particularly of the gate type. The extension 10' of the pressure line connects with the drain pipe 12 which extends through the control valve 13 and is provided with the extension 12' which serves to lead the drain to any desirable point. Rockably mounted on the standard 9 is an operating lever 14. The valve stem 15 of the valve 11 is pivotally connected to the link 16 which is bifurcated at its upper end and embraces the lever 14, this bifurcated portion having a bolt 17 projected therethrough for engaging in a notch 18 formed in the upper edge of the lever 14. A spring 19 embraces the link 16 and engages at one end the under-surface of the lever 14 and at the opposite end the outwardly projecting lugs 20 formed on the lower end of the link 16. A spring 21 serves normally to maintain the lever rocked to the position shown in dotted lines in Fig. 1 which is the position in which the valve 11 would be retained closed. The valve stem 22 of the valve 13 is similarly connected to the lever 14 by the link 23 which is provided with the lugs 24 and which is embraced by the spring 25. These springs embracing the links serve as shock absorbers in the operation of the device and also serve to normally retain a pressure on the valve 11 maintaining it closed.

Mounted on the standard 8 is a latch 26 which is normally held by the spring 26' in position to engage the lever 14. An arm 27 projects outwardly from this latch 26.

Mounted on and projecting upwardly from the base 7 is a chair 28 projecting upwardly from which is the standard 29 on which is pivotally mounted intermediate its ends the bar 30, pivotally connected at one end by the link 31 to the arms 32 and 33 intermediate their ends. The arm 32 is provided with the laterally turned end 34 adapted to lie in the path of and be engaged by the lever 14 when it is rocked to position for closing the valve 11. The arm 33 is laterally offset outwardly from the arm 32 and provided with the downwardly projecting end 35 positioned over and

adapted to engage upon rocking downward the latch arm 27. A spring (although a weight may be used) 36 connects at one end to the arms 32 and 33 and at the opposite end to the post 37 which is mounted in the base 7 and serves normally to move the arms 32 and 33 downwardly so that the end 35 may engage the latch arm 27 and rock it into position to release the lever 14 for rocking movement to open the valve 13 and close the valve 11. When the arms 32 and 33 are rocked downwardly, it is necessary that the bar 30 be rocked also. Rockably mounted on a lug 38 projecting upwardly from the chair 28 is a latch 39 which is adapted to engage the end of the bar 30 and prevent its rocking so that the latch thus serves to prevent a rocking of the arms 32 and 33 in response to the pressure of the spring 36 or weight. Supported on the standard 9 is an electromagnetic coil 40 extending across the cores of which is the pivotally mounted arm 41 having the angularly turned end 42 provided with the screw 43 which is adapted to engage a plate 44 fixedly mounted on the end of the latch arm 39. A spring 45 is attached to this latch arm and serves normally to retain it in position. A plate 46 is mounted on the standard 9 and serves to insulate the electro-magnetic coil from the support 9. Secured to and projecting upwardly from the plate 46 is a post 47 made from suitable electrical conducting metal. Pivotally mounted on the post 47 is a contact arm 48 having a contact shoe 49 (see Fig. 6) adapted to engage the contact 50 carried on the insulating plate 51 which is mounted on the lever 14. Projecting outwardly from the post 47 is an arm 52 connected to which is one end of a spring 53, the other end connecting to the arm 48 and serving normally to maintain the arm 48 rocked downwardly. The contact 50 is connected by the wire 54 to the magnetic coil. The contact shoe 49 is connected by the wire 54 to a source of electrical energy (not shown). The arrangement is such that when the lever 14 is rocked to the position to retain the valve 11 in open position, the contact shoe 49 will be in engagement with the contact 50. The electro-magnetic coil is connected by the wire 55 through a suitable thermostat (not shown) to a source of electrical energy.

In operation, when the lever 14 is rocked to the position shown in full lines in Fig. 1, the drain valve 13 will be closed and the valve 11 will be opened, thus permitting the passage of the material through the pressure line. When the temperature at the location of the thermostat reaches a predetermined point, the circuit to the electro-magnetic coil 40 will be closed. This will cause a rocking of the arm 41 so as to rock the latch 39 and permit the spring 36 or weight to rock the arms 32 and 33. The arm 33 will effect a

release of the latch 26, thus permitting the lever 14 to rock into a position to close the valve 11 and open the valve 13. It will be noted that when the valve 13 is opened and the valve 11 closed that the shoe 49 does not engage the contact 50 so that the current passing through the electro-magnetic coil is of very short duration. 70

It is believed evident that by attaching to the lever 14 the necessary contacts, an electric pump could be set into operation at the same time that the drain control valve is opened, thus effecting a forced draining of the pressure line extending beyond the pressure line control valve 11. 75

In this way, there is provided a device which will automatically control the operation of one or more valves. The device is especially adapted for mounting in homes to control the flow of water through the water pipes in the winter so that a freezing and bursting of the pipes will be prevented. 85

It is believed obvious that the device described may be coupled to any number of valves or similar controls and need not be limited to a single pair. 90

While I have illustrated and described the preferred form of my invention, I do not wish to limit myself to the precise details of structure shown but desire to avail myself of such variations and modifications as come within the scope of the appended claims. 95

Having thus described my invention, what I claim as new and desire to secure by Letters Patent is:

1. A pressure line control of the class described adapted for use with a pressure line, comprising: a valve interposed in said pressure line for controlling flow of fluid therethrough; a drain connected to said pressure line; a valve positioned in said drain for controlling flow of fluid therethrough; a rockable member pivoted intermediate its ends and connected at opposite sides of its point of pivot to said pressure line valve and to said drain control valve and adapted upon rocking in one direction for moving one of said valves to closed position and the other valve to open position, and upon rocking in the opposite direction for moving said valves to opposite positions; resilient means for normally rocking said rockable member to position for closing the valve in said pressure line and opening the valve in said drain; a latch for latching said rockable member in position to maintain the valve in said pressure line in open position; and electrically operated means adapted upon closing of a circuit thereto for releasing said latching means. 110

2. A pressure line control of the class described adapted for use with a pressure line, comprising: a valve interposed in said pressure line for controlling flow of fluid therethrough; a drain connected to said pressure line; a valve positioned in said drain for con- 115

trolling flow of fluid therethrough; a rockable member pivoted intermediate its ends and connected at opposite sides of its point of pivot to said pressure line valve and to said drain control valve and adapted upon rocking in one direction for moving one of said valves to closed position and the other valve to open position, and upon rocking in the opposite direction for moving said valves to opposite positions; resilient means for normally rocking said rockable member to position for closing the valve in said pressure line and opening the valve in said drain; a latch for latching said rockable member in position to maintain the valve in said pressure line in open position; a pivotally mounted arm controlled by an electrically operated means adapted upon closing of a circuit thereto for releasing said arm; resilient means for moving said arm for releasing said latch, and means for breaking the circuit to said latch releasing means upon release of said latch.

In testimony whereof I have signed the foregoing specification:

25 ROMEO S. WOOD.
